Attorney

Patented June 15, 1926.

UNITED STATES PATENT OFFICE.

WALTER MUNCH, OF SUPERIOR, WISCONSIN, ASSIGNOR TO SYPHONIX REFRIGERATOR COMPANY, OF SUPERIOR, WISCONSIN, A CORPORATION OF WISCONSIN.

REFRIGERATED SHOW CASE.

Application filed July 25, 1925. Serial No. 46,042.

This invention relates to show cases, and has special reference to a combination refrigerator, show case, and work counter.

The principal object of my present invention is that of producing a simple and efficient article of this character and one particularly designed with means for maintaining a uniformly constant level of brine therein.

10 Another object is to provide novel means for caring for the refuse from the articles being displayed and preventing their being deposited within the brine.

15 Other objects and advantages of the peculiar combination will appear in the further description of the invention.

20 The accompanying illustration, in which like reference characters indicate like parts, is a vertical section through one of the proved refrigerated show cases, the longitudinal shape and dimensions of which are not material to the invention.

25 1 represents one of the fabricated pedestal supporting sections, the front of which, beneath the show case, may be paneled, as at 2, if desired. On top of this support rests the show case, comprising the pyramidal shaped portion 3 having glazed front and back sides, as at 4 and 5 respectively, and adjacent which latter is the work counter 6. Beneath the work counter is a relatively 30 deep chamber 7, forming that portion of the refrigerating chamber in which the ice or other cooling medium may be deposited, and this cooling chamber extends forwardly beneath the display chamber 8 of the show case, the latter chamber being provided with a removable bottom 9 spaced upwardly from the bottom 10 of the refrigerator space, and 35 inclined slightly downwardly and forwardly so as to drain into the refrigerator space.

40 The bottom of this latter, and in fact the entire show case, is inclined in the opposite direction towards the rearmost corner and 45 suitably insulated in any desired manner.

Beneath the rearmost corner of the refrigerator space and built into the bottom of the show case is a funnel-like drain tube, indicated at 11, and above this drain tube, with- 50 in the refrigerator tank which forms the refrigerating space, is the upstanding drain tube 12, the same being surrounded by suitable insulation 13 to prevent heat entering the refrigerator space through said tube 12, 55 and the latter is surmounted by the cap 14

which is larger in diameter than said tube, including the insulation thereabouts. This cap rests in any desired manner upon the upper end of the tube as by the depending clip 15, so that the lower edges of the cap 60 project considerably below the upper end of the tube and its insulation; thus providing a space about the tube which acts as a water seal and yet will permit of the brine overflowing into the tube when it rises above 65 the end thereof.

The drain tube is just sufficiently high to maintain a level of brine some distance below the bottom 9 of the display space so that air may circulate forwardly beneath the 70 bottom 9 and upwardly through the perforated grid or screen 16 which spans the space between the forward edge of the bottom 9 and the inwardly arched moulding 17 of the 75 front corner of the show case.

There is shown at 18 a drain plug which opens into the upper end of the drain tube so that in the event of wishing to drain all of the brine from the case, the same may be 80 accomplished by the removal of the plug 18.

This novel arrangement is for the particular purpose of convenience in assembling the brine tank within the show case, as the same is shoved into the case from the back during construction, thus having a flush bottom with both discharge openings therein occurring directly above the tube 11, insuring drainage thereof through said tube. 85

It is apparent that any refuse flowing 90 down the bottom 9 with the moisture returning into the brine tank will be caught on the grid 16 in back of the moulding 17 where it will not be conveniently seen from the front of the show case. The rearmost edge of the bottom or shelf 9 is supported 95 by horizontally spaced upright brackets 19 and the back wall 20 of the show space is supported upon these brackets and preferably carries a mirror 21 therein. This back wall 20 terminates short of the upper corner intermediate of the inclined back of the show space and the top of the refrigerator space so as to permit of ready air circulation therethrough.

100 From the above it is apparent that when ice with salt is placed within the refrigerator space it will form a brine that will extend entirely across the lowermost portion of the refrigerator space beneath the display space and that the cold air thus formed will natu- 105

rally circulate upwardly through the grid 16, thence upwardly and backwardly into the upper edge of the display space indicated at 7.

5 Having thus described my invention, what I claim and desire to secure by Letters Patent, is:

1. A refrigerated show case of the character described including a front wall comprising an upper transparent portion and a lower opaque portion, a grid adjacent and concealed from view by said opaque wall, and an elevated floor inclined toward said grid so as to drain therein substantially as 10 and for the purpose described.

2. A show case of the character described including a display compartment, an elevated floor therebeneath, a downwardly stepped grid adjacent the forward edge of the floor, a refrigerant containing tank extending beneath said floor and rearwardly thereof, said tank having an upstanding water sealed drain pipe and a funnel shaped drain tube in the bottom proper of the show case for registration with the drain tube in the refrigerant tank, and a plug for said drain tube. 20 25

In testimony whereof I hereunto affix my signature.

WALTER MUNCH.
